UNITED STATES PATENT OFFICE.

THOMAS W. GREEN, OF PHILADELPHIA, PENNSYLVANIA.

CASING FOR IMPELLERS OF ROTARY BLOWERS.

1,046,773.

Specification of Letters Patent.

Patented Dec. 10, 1912.

Application filed May 10, 1912. Serial No. 696,309.

To all whom it may concern:

Be it known that I, THOMAS W. GREEN, a citizen of the United States, and a resident of Philadelphia, Pennsylvania, have invented a certain new and useful Casing for the Impellers of Rotary Blowers, of which the following is a specification.

The purpose of my invention is to save in weight and thickness of metal economizing both in this way and in the cost of machining the casings for impellers such as are used in blowers, exhausters and pumps.

A further purpose of my invention is to substitute rolled sheet or plate material for cast iron in the curved outer casing parts of rotary blowers, exhausters or pumps.

A further purpose of my invention is to enable the manufacturer to finish the outer curved surfaces of the cast ends or heads of blowers, etc., in a lathe, boring mill or other rotary metal-working machine.

A further purpose of my invention is to inclose within an extension of the casing the gearing which keeps the impellers in step and drives one impeller.

Further purposes of my invention will appear from the specification and the claims.

I have preferred to illustrate my invention by one form thereof which I have determined to be light, inexpensive and efficient, and which well illustrates the principles thereof.

Figure 1 is a top plan view of the preferred form of my casing applied to a blower. Fig. 2 is a vertical section of the structure of Fig. 1, with a portion of the casing removed. Fig. 3 is an elevation of the structure shown in Figs. 1 and 2, viewed from the pulley end but with the pulley removed. Fig. 4 is a section of the form shown in Fig. 1 taken upon lines $\alpha-\alpha$ thereof.

The manufacture of impeller casings, particularly for the larger size blowers that weigh several tons has involved much difficulty and a great expense. These casings have heretofore been cast and a large percentage of them has been spoiled in the molding, even when conditions have been the most favorable. Frequently the rough castings contain blow holes and other imperfections that are not discovered until a great amount of time and labor has been expended thereon. The great size of the flasks required and the difficulty in holding the parts in place during the casting operation, combine to make the foundry work very expensive and trouble-

some. The twisting of the flask as well as the uneven cooling require excessive allowance of material for machining, resulting in a waste of metal which is paid for at foundry prices, including labor, and is sold as scrap. The finished cast casing is many times uneven in thickness, excessively heavy and bulky and cannot be divided to the best advantage because of the machining required. During the machining and setting up, the casings are frequently strained with the result that the impellers and casings do not always register accurately.

My invention is intended to overcome all of the difficulties stated and to produce a lighter, stronger and cheaper casing, with which the impellers can more easily be made to register.

My invention is shown as applied to a rotary blower of the type having two impeller members, the outer end of the blade of each forming a seal with the waist of the other. Evidently it is applicable also to other forms of blowers and pumps. In the double impeller pumps and blowers the central section, within which the inlet and outlet air connections are made, is preferably straight from side to side in the middle section, as indicated at 1 and 2 of the preferably cast central section 3 which I have shown as secured to the base in any suitable manner. Upon either side of this central section, with the two-impeller construction shown, is located a semi-cylindrical casing or shell, shown at 5 and 6 respectively, corresponding closely in shape to the part of the extreme outer portion of the blade of the impeller upon that side of the blower or pump. This outer portion of the impeller, in the form shown, is provided with the packing 7. At the ends the semi-cylindrical side casing parts are closed by semi-circular heads 9, 9' and 10, 10'. With other multi-blade constructions, the portion of the circumference represented in the semi-cylinder and the semi-circle respectively, will differ in accordance with the construction of the machine and will not always represent as much as half of a circle. The application of my invention to these forms will sufficiently appear from the illustration here shown.

It has been customary to cast the entire outer casing or shell, dividing in various ways as may be required for the necessary coring and to provide for the accessibility of the impeller parts from the end thereof.

These cast casings have been excessively heavy.

I have found that the casing may be separated vertically parallel to the impeller axes 5 to advantage, along the edges 11, 12, between the central straight portion and the semi-cylindrical side parts; that the semi-circular ends upon the same side may be cast separately and covered with semi-cylindrical 10 plate side walls; and that the ends may be trued up along the faces thereof which engage with the central straight part and fastened each to the other so as to be finished upon a boring bar or lathe as one circular head, greatly saving in the expense of finishing.

For convenience, I split the intermediate portion 3 up into four parts comprising the two end plates 13, 14 and the top and bottom 20 frames 15 and 16. Each of the central end plates preferably provides bearing for one half of an impeller shaft upon each side as at 17, 18 and is stiffened at these bearings horizontally by web 19 and vertically by 25 flanges 20 and 21 stiffened transversely at 20' and 21'. At the top and bottom, flanges 22 and 23 are shown. The flanges 20, 21, 22 and 23 are effective to join the parts to mating flanges upon the semi-circular end plates 30 and the top and bottom central sections by any suitable fastenings, shown at 24. The caps 25, 26 coöperate upon each end with the bearing members 17, 18 to complete the bearings for the shafts 27 and 28 and are held 35 in place by any suitable means, such as the bolts 29 shown. The ends 9 and 10, as well as the central section 13 at this end, are provided with partition walls 30 for the semi-circular ends and 31 for the central end sections, coöoperating to close the interior of the 40 casing at this point against each other and the impeller shafts. Outside of this partition, however, an elongated gear cover or housing is formed by side walls 32, 33 and 45 end walls 34, 35 parallel with the partitions 30 and 31 to inclose and protect the gears 36 by which the impeller shafts are maintained in uniform rotation and both are impelled by pulley 37. The housing thus 50 formed additionally stiffens this end of the impeller casing to which the driving pulley is connected and upon which the strain is correspondingly increased.

I have illustrated two impellers 38 and 39 55 of a type claimed by me in my Patent No. 1,004,776 and here intended to represent conventional impellers. The portions of the travel of each farthest from the other, represented by the path of the outside of each 60 impeller blade outside of the intermediate casing sections, is in substantial contact with the semi-cylindrical side portions 5 and 6 to whose construction my invention as here illustrated partly applies. The semi-circular heads 9 and 9' and 10 and 10' after being

faced on their straight edge portions are clamped together and turned in any suitable manner, as upon a boring mill, to turn off the circumferences 40, 40' of one set and 41, 41' of the other set at a single operation, 70 preferably turning off the circumferences of all of the semi-circular end pieces at the same operation as the simplest way of insuring the same diameter for each. They may be bored for the shaft at the same setting. The semi-circular end pieces may then be conveniently clamped against the flanges 20 and 21 at the respective ends after these flanges have been faced to the desired distance between their outer faces. I then bend sheets or plates of 80 metal, suitably flanged at their side edges as at 42, temporarily using an internal form between the ends where the separation of the end pieces makes this desirable, and riveting or otherwise fastening the plate metal 85 to the flanges 43 and 44 at any suitable intervals. The flanged edges 42 are preferably secured to the flanges 45 of the top and bottom intermediate sections. Any desired stiffening or external support may be given to 90 the semi-cylindrical sheets of metal thus formed by external re-inforcing strips or sections 46 here shown as of T section and spaced at any suitable intervals. The sheet metal may ordinarily be secured to the 95 flanges at the ends with sufficiently tight sealing contact, without the use of gaskets. Where the intended pressure is relatively high, or where for any other reason leakage is feared or found to exist, any kind of packing 100 may be inserted to improve or secure the joint or the edge may be calked for the same purpose.

In the assemblage of my device, the central frame parts can be erected and the impellers lifted to place before the semi-cylindrical side pieces are fitted on and before or after the top member 15 is placed. These parts are then readily applied. Either of the impellers may be removed by removal of the one semi-cylindrical side piece with its end pieces attached and entire lateral withdrawal of the impeller until it will swing clear of the top piece 15, when it may be lifted out either upwardly or axially. 110 Where the space does not permit this, it can be lifted out just sufficiently to clear from the half bearing of the middle section and the top section 15 removed, permitting free lifting of the impeller. 115

It will be evident that I save the additional weight and cost of metal otherwise required for reliable cast iron covering of the semi-cylindrical surfaces replaced by plate metal as well as the additional metal 125 which would have to be cast initially upon these castings and subsequently removed by boring at large expense.

It will be evident that I make the interior of the blower casing much more easily ac- 130

cessible than has previously been the case, greatly facilitating the placing of my blower close to a wall or other objectionable limiting surface.

5 Having thus described my invention, what I claim as new and desire to secure by Letters Patent is:—

1. In a device of the character stated, a central impeller casing section, semi-circular end pieces attached thereto and a sheet metal covering extending from one semi-circular end piece to the other upon the same side of the blower and means for retaining the parts together.

15 2. In a device of the character stated, a central impeller casing section carrying partial shaft bearings having the journal openings extending in opposite directions in combination with the side sections therefor se-

20 cured to the central section and complementary shaft caps coöperating with the bearing blocks.

3. In a device of the character stated, a central impeller casing section, top and bottom parts therefor, semi-circular end side sections supported by the central section and corresponding in semi-circular contour to the path of travel of the outside of the impellers, impellers fitting within the casing 30 and a side cover member fitting the contours of the end side sections and adjoining those upon the same side.

4. In a device of the character stated, a central impeller section end, side sections 35 fitting thereto and having curved peripheries fitting in contour the paths of travel of the outside of the impeller wings used, impellers adapted to be used in the casing and side casing members fitting the curved con-

40 tours of the end side sections and secured thereto.

5. In a device of the character stated, a central section having partial shaft bearings

thereon, removable top and bottom parts therefor and semi-cylindrical side sections 45 and means for securing the sections together.

6. In a device of the character stated, central sections provided with side, bottom and top flanges at each end, top and bottom 50 members provided with end flanges co-operating with the flanges of the central section and oppositely facing cylindrical side sections having flanges at each end coöperating with the side flanges of the central 55 section.

7. In a device of the character stated, end members provided with vertically divided bearings, a web connecting adjoining bearing parts, vertically disposed webs supporting the said bearing parts and top, bottom and side members adjoining the ends.

8. In a device of the character stated, a central casing member, semi-circular end side portions secured thereto at opposite 65 ends of the casing and semi-cylindrical side members secured to the semi-circular ends.

9. An impeller casing having separable semi-circular flanged end side members and semi-cylindrical side connecting portions 70 united to the flanges.

10. A pair of impellers, shafts therefor, an impeller casing vertically divided longitudinally through the axes of the impeller shafts, and means for uniting the parts at 75 the planes of division.

11. In a device of the character stated, centrally and oppositely disposed side casing members divided along parallel vertical planes, bearings divided along the planes of 80 casing division and vertically disposed flanged supports for said bearings.
